FORCED DRAFT PRODUCING DEVICE

Filed Dec. 13, 1929

Inventor,
Joseph W. Bragstad,
By: John W. Bragstad

UNITED STATES PATENT OFFICE

JOSEPH W. BRAGSTAD, OF ELMHURST, ILLINOIS

FORCED-DRAFT-PRODUCING DEVICE

Application filed December 13, 1929. Serial No. 413,801.

This invention relates to improvements in devices for producing forced drafts, particularly adapted though not necessarily limited in its use, for hot air furnaces, and one of the objects of the invention is to provide improved means for drawing cold air out of a house or room and for forcing warm air thereinto.

A further object is to provide improved means for filtering the air supply to the fan and improved means whereby when the fan is rendered inactive the filter will be automatically adjusted so as not to interfere with or obstruct the natural circulation of air around the fan and to the furnace.

A further object is to provide improved means including a damper for cutting off the free circulation of air when the fan or blast producing device is active and means responsive to the movement or adjustment of the said damper for controlling the operation of the fan or blast creating device.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a view partly in elevation, partly in vertical section and partly broken away, of a device of this character constructed in accordance with the principles of this invention and showing the same as used in connection with a flue, and with the parts in position so as to permit a free and natural circulation of air to the furnace.

Figure 2 is a detail sectional view taken on line 2—2, Figure 1.

Figure 3 is a view similar to Figure 1, showing the parts in a different position with the damper closed to produce a forced cir-

culation and the filter correspondingly adjusted.

Referring more particularly to the drawing the numeral 10 designates generally a flue of any desired size and configuration for receiving and conducting cold air away from a room or house. This flue may have communication with the room through the floor 11 thereof and by means of the ordinary registers or grating 12.

The flue may be of any desired size and configuration and communicating therewith and preferably adjacent the top thereof through an opening 13, is an auxiliary flue 14, which latter has communication as at 15 with a furnace 16.

Arranged in an opening in the wall between the flue 10 and the auxiliary flue 14 is a blast creating device, such as a fan designated generally by the reference numeral 16, and the fan is preferably arranged in alignment with the opening 15 leading to the furnace.

Within the flue 10 is a filter bag 18 which is constructed of any desired or suitable material and is held against normally collapsing in any desired or suitable manner. The lower end of the filter is open and is connected as at 19 with the fan casing, and the upper end 20 of the filter is closed and is supported in any suitable manner such as by means of a cord or chain 21, one end of which is fastened as at 22 to the end 20 of the filter and the cord or chain passes over a suitable pulley or other device 23 supported by the wall of the flue and may pass through suitable guides 24 to a position in proximity to an opening 25 preferably adjacent the base of the flue and may be anchored as at 26. A door 27 forms a closure for the opening 25. Arranged preferably adjacent the bottom of the opening 13 between the flues is an arm 28 which is connected with a damper or slide 29, the latter being adapted to be moved from the position shown in Figure 1 to the posi-

tion shown in Figure 3, to close the opening 13 and when so moved, the arm 28 will be moved therewith. Supported by the arm 28 is a pulley 30 over which the flexible member 21 passes so that during the raising and lowering movements of the damper 29 and consequently the arm 28, the end 20 of the filter will be correspondingly raised or lowered for a purpose to be set forth. When, however, the arm 28 reaches the limit of its lowermost movement or even at the limit of its uppermost movement the filter 18 may be lowered with respect to the arm 28 by detaching the flexible member 21 from its anchor 26.

A lever 31 is pivotally mounted as at 32 upon a suitable support preferably one of the walls of the auxiliary flue and is connected by its other end by means of a pin and slot connection 33-34 with the arm 28 and serves as a means for raising and lowering the arm 28 and the damper 29. This may be effected in any suitable manner preferably by means of a pull cord or chain 35 leading to any suitable point. Thus it will be seen that when the pull cord or chain 35 is drawn upwardly from the position shown in Figure 1, the lever 31 will be rocked about its pivot and this will raise or close the damper 29 and also raise the arm 28 to also raise or extend the filter 18.

The opening 13 and damper 29 are provided for the purpose of permitting a free circulation of air when the draft or blast creating device is inactive as it will be observed that when the parts are in the position shown in Figure 1, the blast creating device or fan is inactive and with the parts as shown in Figure 1, free air will circulate through the grating 12 into the flue 10, out of the opening 13, through the auxiliary flue 14 and into the furnace. At this time it is advisable to drop the filter 18 so that it will not interfere with or obstruct such free circulation of air and this is accomplished through the medium of the arm 28.

When, however, it is desired to produce a forced draft, and to change the direction of flow of air, so that the air instead of flowing through the opening 13 into the flue 14 will flow through the filter 18, the lever 31 is rocked to raise the arm 28 and damper 29 to close the opening 13 and as the damper 29 is being raised or closed the arm 28 co-operating with the flexible member 21 will move the parts into the position shown in Figure 3 and thereby close the opening 13. In this position and when the fan is operating it will be manifest that the air drawn into the flue 10 must pass through the filter 18 before being discharged into the furnace.

It is advisable that the damper 29 is open or in the position shown in Figure 1, to shut off the blast producing device and when the damper 29 is closed, to start the blast producing device. This may be effected in any

suitable manner, preferably through the medium of a switch 36 having an operating handle 37 of the ordinary type which moves the handle in one direction normally under spring pressure. To this handle 37 is connected a pull cord or chain 38 which is connected as at 39 with the lever 31. Thus when the lever 31 is moved from the position shown in Figure 1 to the position shown in Figure 3, the damper 29 will be closed and the switch 36 will be operated to start the blast producing device 17. When the damper 29 is opened and the lever 31 moved to the position shown in Figure 1, the pull cord or chain 38 will become slack and the normal tendency of the switch 36 will cause the lever 37 to move in a direction to interrupt the circuit to the blast producing device 17 and thereby cause the same to stop.

A cord or chain 40 may be provided as a means for anchoring the portion of the filter adjacent the blast creating device 17 so as to prevent the same from being drawn into the blast creating device by the suction thereof.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. In combination a flue, a tubular filter in the flue, an auxiliary flue having communication with the first said flue, a damper for closing said communication between the flues, means whereby the movement of the damper to open said communication will move the filter into a position out of the way with respect to said communicating opening to allow the air free access to said opening, means for controlling the movement of the damper at will, and means for inducing circulation of air through said filter when the said damper is closed.

2. In combination a flue, a tubular filter in the flue, an auxiliary flue having communication with the first said flue, a damper for closing said communication between the flues, means whereby the movement of the damper to open said communication will move the filter into a position out of the way with respect to said communicating opening to allow the air free access to said opening, means for controlling the movement of the damper at will, means for inducing circulation of air through the filter when the damper is closed, and means responsive to the movement of the damper for controlling the operation of the said circulation inducing means.

3. In combination, a flue having an outlet, a tubular filter in the flue, means adjacent said outlet for inducing circulation of air

through the flue and filter and through said outlet, an auxiliary flue having communication through an opening with the first said flue and also provided with an outlet, a damper for controlling said communication between the flues, means for adjusting the damper, and an operative connection between the damper and a portion of the filter whereby the filter will, by the movement of the damper, be positioned out of the way with respect to said communicating opening.

4. In combination, a flue having an outlet, a tubular filter in the flue, means adjacent said outlet for inducing circulation of air through the flue and filter and through said outlet, an auxiliary flue having communication through an opening with the first said flue and also provided with an outlet, a damper for controlling said communication between the flues, means for adjusting the damper, an operative connection between the damper and a portion of the filter whereby the filter will, by the movement of the damper be moved out of the way with respect to said communicating opening to allow the air free access to the opening, and means operating automatically to start and stop the operation of said circulation inducing means upon the operation of said damper.

5. In combination, a flue having an outlet, a tubular filter in the flue, means adjacent said outlet for inducing circulation of air through the flue and filter and through said outlet, an auxiliary flue having communication through an opening with the first said flue and also provided with an outlet, a damper for controlling said communication between the flues, means for adjusting the damper, an operative connection between the damper and a portion of the filter whereby the filter will, by the movement of the damper, be moved out of the way of said opening, and means operating automatically to start and stop the operation of said circulation inducing means upon the operation of said damper, all of said parts being housed within the respective flues.

6. In combination a flue having a discharge outlet adjacent one end, a fan adjacent said outlet for inducing circulation of air through said flue and through said outlet, an auxiliary flue having communication with the first said flue at a point remote from said outlet, said auxiliary flue having an outlet, a damper for controlling the communicating opening between the flues for changing the path of circulation of the air, a filter in the first said flue and through which filter the air must pass to flow through the outlet of the first said flue, and means whereby the operation of the damper in one direction will move the filter out of the way with respect to the said communicating opening of the flues.

7. In combination a flue having a discharge outlet adjacent one end, a fan adjacent said

outlet for inducing circulation of air through said flue and through said outlet, an auxiliary flue having communication with the first said flue at a point remote from said outlet, said auxiliary flue having an outlet, a damper for controlling the communicating opening between the flues for changing the path of circulation of the air, a filter in the first said flue and through which filter the air must pass to flow through the outlet of the first said flue, means whereby the operation of the damper in one direction will move the filter out of the way with respect to the said communicating opening of the flues, and means whereby the operation of said damper will control the operation of the said air circulation inducing means.

8. In combination a flue having an outlet, a fan adjacent said outlet for inducing air circulation, a filter in the flue through which the air must pass to said outlet, an auxiliary flue, a communicating opening between the flues at a point remote from said fan, a damper for controlling said communicating opening, means for adjusting the damper, means whereby the filter will be moved out of the way with respect to the said communicating opening, and means whereby the circulation creating means will be rendered active upon the closing of said damper and inactive upon the opening of the damper.

9. In combination a flue having a discharge outlet, a fan adjacent said outlet, a filter in said flue and through which filter air must pass to said outlet, a second outlet for the flue separate from the first said outlet, a damper for controlling the said second outlet, and means for causing the filter to be moved out of the way with respect to said second outlet when the damper is opened, to permit circulation of air through the last said outlet without passing through the filter.

10. In combination two flues having communication with each other at separated points, an outlet from one of the flues, a fan adjacent one of the communicating openings, a filter in the other flue through which air must pass to said fan, a damper for closing the other of said communicating openings, the last said opening serving as a passage for air from the filter containing flue to the other flue without passing through the filter, and means whereby the adjustment of said damper in one direction will move the filter out of the way with respect to the damper controlled opening to permit free access of the air to said opening.

11. In combination two flues having communication with each other at separated points, an outlet from one of the flues, a fan adjacent one of the communicating openings, a filter in the other flue through which air must pass to said fan, a damper for closing the other of said communicating open-

ings, the last said opening serving as a passage for air from the filter containing flue to the other flue without passing through the filter, means whereby the adjustment of said damper in one direction will move the filter out of the way with respect to the damper controlled opening, and means responsive to the operation of the damper for controlling the operation of the fan.

10 In testimony whereof I have signed my name to this specification on this 6th day of December, A. D. 1929.

JOSEPH W. BRAGSTAD.
